CLAIM

The ornamental design for a comb apparatus, as shown and described.

DESCRIPTION

FIG. 1 is a top isometric view of an ornamental design for a comb apparatus, showing teeth elements extending outwardly from the top surface of a base member.

FIG. 2 is a bottom elevation view thereof, showing the bottom surface of the base member of the comb apparatus.

FIG. 3 is a side elevation view thereof; and,

FIG. 4 is a bottom isometric view thereof.

The broken line showing the hanging loop in FIG. 2 is for the purpose of illustrating environment and forms no part of the claimed design.
